AUTOMATIC STARTER FOR ELECTRIC MOTORS.

1,120,709.

Specification of Letters Patent.

Patented Dec. 15, 1914.

Original application filed May 26, 1905, Serial No. 262,318. Divided and application filed June 27, 1906, Serial No. 323,671. Divided and this application filed June 14, 1907. Serial No. 378,910.

To all whom it may concern:

Be it known that I, ERNEST L. GALE, Sr., a citizen of the United States, residing at Yonkers, in the county of Westchester and State of New York, have invented a new and useful Improvement in Automatic Starters for Electric Motors, of which the following is a specification.

My invention relates to apparatus for controlling electric currents, and more particularly that used for starting and controlling electric motors.

This application is a division of my co-pending application, Serial No. 323,671, filed June 27, 1906, for improvements in automatic starters for electric motors, which itself is a division of my application filed May 26, 1905, Serial No. 262,318.

One of the objects of the invention is the provision of automatic means for starting and controlling an electric motor with maximum efficiency.

Other objects of the invention will appear hereinafter, the novel combinations of elements being pointed out in the appended claims.

Referring to the accompanying drawings, Figure 1 represents diagrammatically one form of my invention in which a magnet switch is used to close the controlling circuit; and Fig. 2 illustrates a modification in which a retaining circuit for a main line circuit maker is used.

1 designates the motor armature.

4^A and 4^B designate resistances, which are in series with the motor armature when the main motor circuit is closed. These resistances are proportioned in the usual way to prevent too much current from passing through the motor upon starting the same.

The mains designated by the signs + and - are connected directly to the motor armature and the contact 6^E, respectively, as shown. In Fig. 1 the field coil 9 is connected to the positive main to the left of the motor armature and to the main armature circuit between the resistance 4^B and the electro-magnetic switch 10. The field circuit is therefore in shunt to the motor armature and the starting resistance.

The controlling circuit is connected in parallel to the sectional starting resistance and includes the solenoids 2^A and 2^B and a manual switch 11 which is arranged to open

and close said controlling circuit. The starting resistance may be divided into any number of sections with a corresponding electro-magnetic switch for each section; or said starting resistance may consist of only one section, in which case only the electro-magnetic switch comprising the solenoid 2^B will be necessary. The solenoid 2^A is arranged to act on its core or plunger 8 to lift the contact maker, bridge piece or resistance varying member 7, which is connected thereto, so as to disconnect or move away said resistance varying member from the contacts 5 and 6, and thus insert the resistance 4^A so that it will be in series with the motor armature when the main circuit through the latter is closed. Normally the resistance 4^A is short-circuited through the low resistance conductor 12 and the resistance-varying member 7. The solenoid 2^B acts in a similar manner to lift its plunger 8^B and contact maker or resistance-varying member 7^B away from the contacts 5^B and 6^B to insert the resistance 4^B in series with the motor armature when the main circuit through the latter is closed by the electro-magnetic switch 10. The resistance-varying members 7 and 7^B also act to short-circuit the corresponding resistances 4^A and 4^B when the respective solenoids 2^A and 2^B become sufficiently deenergized.

Arranged above the resistance-varying members 7^B to be engaged thereby, are the fixed contacts 5^C and 6^C connected respectively to the positive main at 13 to the left of the motor armature, as viewed in Fig. 1, and to the solenoid 2^E of the switch 10. The solenoid 2^E is connected to the contact 3^F of the manual switch 11, and the solenoid 2^E is connected to the contact 3^G of said manual switch. These contacts are so arranged that the pivoted lever 3^F when moved to the left will engage first the contact 3^F and then the contact 3^G. This is the preferable arrangement but is not essential, for the reason that if both contacts 3^F and 3^G were electrically connected at once by the lever 3^F, the switch 10 could not be closed because of the resistance 21 connected in circuit with the solenoid 2^E. In this instance this resistance 21 is connected to the contacts 5^C and 6^C and also in series with the solenoid 2^E of the electro-magnetic switch 10.

The screw 15 shown in the fixed support

14 is for the purpose of limiting the upward movement of the core 8, so that when a series of solenoids and switches is used to vary the sectional resistances, said switches 5 may be made to operate successively in permitting their cores to drop.

When the single starting switch 11 is actuated to effect the starting of the motor, the lever 3^E first comes into engagement 10 with the stationary contact 3^F which will connect the magnets 2^A and 2^B across the normally open resistance circuit in which are the resistances 4^A and 4^B and the contacts 5^E and 6^E. When the solenoid 2^A receives 15 current to lift its core followed by 2^B lifting its core, the latter's bridging contact 7^B will connect the two stationary contacts 5^C, 6^C, and thereby short-circuit the resistance 21 which is in circuit with the magnet solenoid 2^E. Now when the switch lever 3^E is moved farther it comes into engagement 20 with the stationary contact 3^G, and thus connects the magnet 2^E across the line or between the + and - terminals. The electro-magnetic switch 10 will then be 25 operated, which results in the contacts 5^E and 6^E being electrically connected by the contact maker 7^E. The switch 10 thus acts as an electro-magnetic main line switch and 30 when the same is closed, the main armature circuit including the armature 1, starting resistance and the contacts 5^E and 6^E and contact maker 7^E is closed. Current will therefore be admitted both to the armature 35 and starting resistance and to the shunt field circuit 9.

The magnet solenoids 2^B and 2^A will operate to allow their cores to drop successively or in the order mentioned, and to short-circuit the sections of resistance 4^B and 4^A as the potential across the starting resistance circuit decreases. As soon as the magnet solenoid 2^B allows its core to drop, it will break the connection between the contacts 5^C and 6^C, and thus reinsert the resistance 21 in the circuit including the magnet solenoid 2^E. This will reduce the current which passes through the solenoid 2^E, but not to a sufficient extent for it to become so deenergized as to allow its core to drop. This resistance 21 is preferably so proportioned that it will not allow sufficient current to flow through the magnet solenoid 2^E to enable it to lift its core when the latter 55 is down, but said resistance will allow sufficient current to pass through said solenoid to hold the core up after it has been lifted. One of the advantages of this arrangement is that if the switch 11 should be closed 60 rapidly, the main armature circuit would not be closed until the starting resistance short-circuits had been broken. The magnet solenoids 2^A and 2^B are arranged in such a way that magnet 2^A will lift its core before magnet 2^B does, in which case the start-

ing resistance will always be increased to its maximum value before the solenoid 2^E will lift the member 7^B to close the main armature circuit. One of the methods for obtaining a successive operation of the solenoids 2^A and 2^B and dropping their cores, is the employment of a different number of windings so as to have different number of ampere turns. For instance, as shown in Fig. 1, the solenoid 2^A has a greater number 70 of turns than the solenoid 2^B. In such case the same amount of current flows through each of these magnet solenoids, and the solenoid 2^A having the greater number of ampere turns will hold up its core longer. Another means for obtaining successive action of the solenoids in lifting or dropping their cores include the adjustable stop screws 15 mounted in fixed supports 14. These stop screws limit the upward movement of the 80 core such that their upper positions in the solenoids vary. For instance, if one core is projecting farther into its solenoid than another core into a corresponding solenoid, the first core will be the first to operate. After 90 attaining their upper positions, those having the weaker fields will be the first to be permitted to descend.

If the line circuit should fail while the starting switch 11 remains closed, the motor will be automatically protected and will not be injured if the line circuit should be turned on again. In such event all three of the solenoids, 2^A, 2^B, 2^E will again be excited with current, but the current flowing 100 through the solenoid 2^E will be limited by the resistance 21, and as this current is not sufficient to enable the solenoid 2^E to lift its core, the main line switch 10 will not be immediately closed. The solenoids 2^A and 2^B 105 will lift their cores and thus change the starting resistance to its maximum volume. The solenoid 2^E will also cause the resistance 21 to be short-circuited so that sufficient current can again pass through the solenoid 2^E 110 to cause the latter to lift its core and effect the closure of the circuit including the armature and starting resistance after the latter has been inserted.

After the resistance-varying members 7 115 and 7^B have been moved upwardly to positions indicated in Fig. 1, it may be said that they then occupy their starting positions, said members normally connecting the contacts 5, 6 and 5^B, 6^B, respectively. 120 As soon as the motor starts up and increases in speed the potential across the starting resistance gradually diminishes, but the solenoids 2^A and 2^B, gradually diminishing in strength, act as retarding means to prevent 125 said members from returning to their normal positions or running positions until the motor has attained a predetermined speed. In other words, the members 7 and 7^B normally short-circuit or cut out the sec- 130

ditional resistances 4^A and 4^B , and as soon as the switch 11 is closed onto the contact 3^F so as to close a circuit through the armature and the solenoids 2^A and 2^B , the latter will lift their cores and move said members upwardly until they occupy their upper positions or starting positions. After the motor has attained a predetermined speed, the same solenoids 2^A and 2^B will permit the members 7 and 7^B to return in a retarded movement to their running positions after the main line switch 10 is closed automatically. It will be noted that after the manual switch 11 has been operated, the starting resistance inserted, and the main line switch closed, the motor will start, and as it increases in speed, less and less current will flow through the solenoids 2^A and 2^B until gravity overcomes their upward pull to gradually move the members 7 and 7^B to their running positions successively in the order named. It should be further noted that it is not until the members 7 and 7^B have been moved to their starting positions that the solenoid 2^B can receive sufficient current to effect the closure of the main armature circuit. The main circuit through the armature and said members therefore remains open at the switch 10 until after the said members leave their initial positions.

If the initial armature circuit including the armature only and the solenoids 2^A and 2^B were of sufficiently low resistance, the armature would start to rotate immediately when the lever 3^E engaged the contact 3^F , inasmuch as the field circuit 9 would at this time be connected across the armature with the starting resistance 4^A , 4^B in series therewith. Preferably, however, the solenoids 2^A and 2^B are made of sufficiently high resistance to prevent the armature from starting until the main armature circuit is closed.

As soon as the controlling circuit is closed the members 7 and 7^B are moved quickly to their uppermost or intermediate positions, although the member 7 is moved up before the member 7^B reaches its uppermost position. If the switch 11 is moved off both contacts 3^F and 3^G quickly the member 7^B closes the main armature circuit very shortly afterward. In fact the starting operation is done very quickly so that even if the controlling circuit were of sufficiently low resistance to permit the motor to operate, it would not have time to start until the main armature circuit is closed. It is evident that so long as there is current in the controlling circuit while the motor is speeding up, the plungers or cores in the solenoids in the controlling circuit will move downwardly with a retarded movement. This retarded movement may be varied. For instance, if the plungers are about the same length as the solenoids, the

movement of each plunger from its uppermost position to a lower position may be considerably retarded, but if the upper ends of the plungers reach only half way into the solenoid when the plungers are in their uppermost positions, the plungers may be permitted to drop more quickly, although successively.

In Fig. 2 I have shown a self-holding or retaining circuit including a solenoid 12^B for assisting the solenoid 2^B in lifting the core 8^B and maintaining the circuit-closing device 10 in closed position so long as the switch lever 3^E is in engagement with the contact 3^G and the mains are sufficiently energized. Parallel with the electro-magnet solenoid 12^B are connected resistance 21 and the electro-magnet solenoid 2^B of the circuit-closing device 10.

When the switch 20 is closed, the field coil 9 will receive current and all the electro-magnets will be energized. Only the electro-magnet solenoid 2^B , however, receives sufficient current to lift its core, whereupon the resistance-varying member 7^B attached thereto will be lifted from the contacts 5^B and 6^B and thus insert resistance 4^B in the armature circuit. The controlling circuit is preferably of high resistance so that the motor cannot be started by the current allowed to pass therethrough. As in Fig. 1, so also in Fig. 2, when the lever 3^E engages the contact 3^G the circuit will be closed including the motor armature and the solenoid 2^B in series with each other, and if this circuit were of sufficiently low resistance the motor armature would start at this point, although the main armature circuit is still open.

The switch 10 may be placed anywhere in the main line circuit, but is preferably connected outside of the shunt field terminals so that the shunt field will not be normally receiving current, that is, the shunt field circuit will not be consuming current while the motor is not being operated.

An additional contact member 7^C is secured to the upper end of the core 8^B in Fig. 2, so that when said core is lifted contacts 5^C and 6^C will be electrically connected to short-circuit the resistance 21. Sufficient current can now flow through the electro-magnet solenoid 2^B to cause the same to lift its core 8^B , together with the bridge member 7^B fastened to and insulated therefrom, so that the contacts 5^E and 6^E will be electrically connected with each other. The circuit including the motor armature and the starting resistance is thus closed to allow sufficient current to pass to start the motor. After the core 8^B has been lifted and brought farther into the field of the solenoid 12^B , the latter will have sufficient strength to hold said core 8^B in its upper position after current has been short-cir-

4
cuated from the electro-magnet solenoid 2^B by the return of the resistance-varying member 7^B to its initial or running position where the member 7^B is again in engagement with the contacts 5^B and 6^B.

From the foregoing it will be seen that it merely requires the closing of a single switch to safely start the motor, and, furthermore, that the motor will automatically and safely start up again after being stopped by a temporary interruption of the main line current supply. This I consider a valuable feature of my invention, as it automatically protects the motor from over-load on starting, whether the current is supplied voluntarily at the will of an operator, or by the reestablishment of current in a line in which the motor is connected; that is, in a circuit including a source of electric supply and conductors connected to those marked + and - in the drawings, usually through a manual two-pole main line switch.

It is to be noted that in each arrangement not only is the current in the armature circuit varied by the operation of the means controlled by the controlling circuit, but that the current in the controlling circuit itself is reduced during the operation; that the magnets in the controlling circuit receive maximum current at the time they are called upon to actuate switches connected thereto, and that this current is reduced to practically zero after they have performed their work. This is accomplished automatically and without the use of any extra switches or other auxiliary apparatus. Because of this feature the magnets may be made smaller than they otherwise might, and the whole apparatus simpler and less expensive.

Obviously those skilled in the art may make various changes in the details and arrangement of parts without departing from the spirit and scope of my invention, and I desire therefore not to be limited to the precise construction herein disclosed.

What I claim as new and desire to have protected by Letters Patent of the United States is:—

50 1. In a starter for electric motors, the combination with a starting resistance for the armature circuit, of a resistance-varying member, an electro-responsive device permanently connected in series with the motor armature for operating said member, a main line switch, an electro-responsive device for operating the switch, and a manual switch for successively closing the circuits of said electro-responsive devices in the order specified.

60 2. In a starter for electric motors, the combination with a starting resistance for the armature circuit, of electro-magnetic devices permanently connected in series with the motor armature for controlling said re-

sistance, an electro-magnetic switch in the armature circuit, and a manual switch movable into positions to successively close the circuits for said devices and said switch, and means for preventing the operation 70 of said switch until the controlling devices have operated.

3. In a self-starter for electric motors, the combination with a starting resistance, of an electro-magnetic switch for inserting said resistance and afterward cutting it out again, and having its magnet winding permanently connected in series with the motor armature, means for closing the supply of current to the motor, a motor armature, 80 and a field circuit permanently connected across that portion of the armature circuit containing the said armature and starting resistance.

4. In a self-starter for electric motors, the combination with starting resistance, of an electro-magnetic switch for first inserting said resistance and afterward cutting it out again, an electro-magnetic switch for the main armature circuit, and an electric switch 90 for first completing a circuit through said first-named electro-magnetic switch in series with the motor armature permanently and then the second-named electro-magnetic switch.

5. In a self starter for electric motors, the combination with sectional starting resistance, of a plurality of electro-magnetic switches for controlling said resistance, an electro-magnetic main line switch, and an 100 electric switch for successively closing first a circuit including the magnet windings of said controlling switches and the motor armature in series, and then a circuit for said main line switch.

6. In a self-starter for electric motors, the combination with starting resistance initially cut out, of an electric switch for controlling said resistance, an electro-magnet for operating said switch, a main armature circuit switch, an electro-magnet for operating the last-named switch, and a switch for successively closing the circuits of said electro-magnets, the circuit of the magnet of the said controlling switch permanently including the motor armature.

7. In an automatic starter for electric motors, the combination with a starting resistance for the armature circuit, of a resistance-varying member, electroresponsive means 120 permanently connected in series with the motor armature for automatically inserting said starting resistance and thereafter automatically cutting it out again, automatic electroresponsive mechanism for closing the main armature circuit after said starting resistance has been inserted, and a single switch consisting of only two contacts and a single circuit-closing member for successively establishing circuits to said electrore- 130

sponsive means and said electroresponsive mechanism.

8. In a self-starter for electric motors, the combination with starting resistance, of a resistance-varying member, an electro-magnet permanently connected in series with the motor armature for moving said member to insert said resistance, said member returning automatically to cut out said resistance again, an electro-magnetic main armature circuit switch, connections effecting the closure of the last-named switch after the resistance has been inserted, and a switch consisting of two stationary contacts in circuit with said electromagnet and the magnet of the armature circuit switch, and a device for connecting said contacts respectively to one of the mains.

9. In a self-starter for electric motors, the combination with sectional starting resistance, of a plurality of electric switches initially in position cutting out said resistance, a controlling circuit in series with the armature of the motor and containing a plurality of electro-magnets, one for each of said switches and operating successively both in opening said switches and in permitting them to close, a main line magnet, a main line switch, a controlling switch for closing the controlling circuit and the main line electro-magnet circuit, and connections comprising a resistance for effecting the operation of the main line magnet to close the main line switch only after the starting resistance has been inserted.

10. In self-starters for motors, the combination with starting resistance, of a plurality of switches connected to said resistance, a controlling circuit having therein a plurality of electro-magnets, one for each of said switches, an electro-magnetic main armature circuit switch, an additional resistance in circuit with the electro-magnet of the last-named switch, and a switch adapted first to close the controlling circuit in series with the motor armature and then the main line magnet circuit successively in the order specified.

11. In a self-starter for electric motors, the combination with sectional starting resistance, of a plurality of electric switches initially cutting out said starting resistance, a controlling circuit including a plurality of electro-magnets one for each of said switches and operating successively both to insert said resistance and cut it out again, a main line magnet, an additional resistance in circuit with said main line magnet to prevent its operation initially, connections effecting the cutting out of said additional resistance after all the starting resistance is inserted, and a switch for closing the controlling circuit to effect flow of current through the same and the armature in series initially, said last-named switch also closing the circuit of the main line magnet to effect the closure of the main line switch to close the main armature circuit and place the controlling circuit across the starting resistance, the controlling circuit being short-circuited after the starting resistance has been cut out step by step as the current through the controlling circuit decreases, due to decrease of potential across said starting resistance.

12. The combination of an electric motor, a starting resistance in the armature circuit, electro-magnetic devices controlling said resistance, an electromagnetic switch in the armature circuit, a manual switch movable into positions to successively close a circuit for said devices permanently in series with the motor armature and a circuit for said switch, a resistance in the magnet circuit of said electromagnetic switch, and means operated by one of said electromagnetic devices to short circuit said last named resistance and thereby permit the operation of said electromagnetic switch.

In testimony whereof, I have signed my name to this specification in the presence of two subscribing witnesses.
